UNITED STATES PATENT OFFICE

WILLIAM P. FROST, OF JACKSON HEIGHTS, NEW YORK, ASSIGNOR TO EVANS ELEVATOR EQUALIZER COMPANY, OF BEDFORD, INDIANA, A CORPORATION OF INDIANA

DEVICE FOR EQUALIZING STRAINS UPON A GROUP OF CABLES CONNECTED TO A STRESS-RECEIVING ELEMENT

Application filed December 26, 1931. Serial No. 583,342.

My invention relates to a device for equalizing the strain upon the members of a group of cables or other tension members connecting two elements subject to a joint stress through such tension members. The particular embodiment of my invention hereinafter described was devised and intended for and because of its small vertical dimensions is especially suitable for use in connecting a group of compensating cables to an elevator car for the purpose of equalizing the strain on such cables. In the art relating to the hoisting of passenger and freight elevator cars by means of a group of hoisting cables, it is established practice to counterbalance the weight of the car by a counterweight connected to the hoisting cables on the opposite end of the cables from the car, and it is well understood that as the cables run over the hoisting or suspension drum between the car and counterweight the weight of the cables is transferred from one side to the other, thus destroying the balance between the car and counterweight. To preserve this balance it is usual to employ a group of compensating cables engaging grooves in a common compensating pulley at the bottom of the elevator shaft and connected at their opposite ends to the bottom of the car and the counterweight, such as the arrangement explained in my copending application for patent filed March 21, 1930, Serial No. 437,684. My present invention will be described with reference to an elevator installation of this kind, and because of the limited clearance below a car at the bottom of the elevator shaft and the small vertical dimensions of the device it is especially suited for such use. It will be understood, however, that in inverted position it is also capable of being used as an equalizing device for connecting an elevator car (or counterweight) to a group of hoisting cables, or in other situations in which a group of cables subject to joint stress are connected to a stress-receiving body or element.

As is well understood in the elevator art, differences in sizes, twist and wear of the compensating, or hoisting cables employed in elevator apparatus, and also slight differences in the circumferential dimensions of the

grooves of the compensating drum or hoisting drum cause the connected cables, in some instances, to have a slightly different degree of travel which, in the case of cables directly attached to the car and counterweight, occasions a difference of stress upon the connected cables, and various kinds of equalizing devices for remedying this defect are known. It is the object of my present invention to provide a simple, efficient and reliable equalizing device of the type employing an equalizing cable engaging pulleys on the cable ends and car which because of its novel arrangement and combination of cooperating parts, shall possess advantages in the way of compactness and simplicity of construction and capacity for equalizing a considerable degree of variation in travel between the cables rendering it highly desirable and efficient for serving its intended purpose. The essential elements of my invention being more particularly pointed out in the appended claims, it being understood, however, that I intend to include all equivalents of the particular parts recited and intend to embrace all variations and modifications of construction falling within the true purpose and spirit of my invention.

In the drawings, Figure 1 is a side view, on a relatively small scale, illustrating a typical elevator installation to which my invention is shown applied;

Fig. 2 is a side view on a larger scale, of my novel equalizing device, and fragmentary portions of an elevator car to which it is secured;

Fig. 3 is a transverse vertical section of the device in a plane indicated by the dotted line 3-3 of Fig. 2;

Fig. 4 is a top plan view of the device; and

Fig. 5 is a vertical section in a plane indicated by the dotted line 5-5 of Fig. 4.

Like reference characters indicate like parts in all the figures of the drawings.

First describing briefly the elevator installation illustrated, it will be understood that the elevator car is suspended by the group of hoisting cables 1, preferably through an equalizing device represented as a whole by the reference numeral 2, which may be of the

type hereinafter described, or of any other suitable type. The hoisting cables travel in the grooves of the hoisting drum 3 at the top of the elevator shaft and are secured at their opposite ends to the counterweight 4. The hoisting cables may be secured to the counterweight directly, as shown, or connected through a suitable equalizing device.

The compensating cables 5 of the installation, five in number in the present instance, which are of the same size and weight, are connected to the bottom of the car by the equalizing device to which the present invention particularly relates, and at the bottom of the elevator shaft engage the grooves of the compensating drum 6 mounted in a vertically slidable frame 7 which is weighted to tension the cables, the other end of the cables being secured to the counterweight. It will be understood that whatever their number, the aggregate weight of the compensating cables is the same, or approximately the same, per unit of length, as the aggregate weight of the hoisting cables.

The frame of an elevator car of ordinary construction includes, as shown, a pair of vertical stile members 8 located one at each side of the center of the car, and a pair of horizontal channel iron supporting members 9 secured to the lower ends of the stiles. Above the channels 9 and supported by them and by connection with other parts of the car, is the platform 10 of the car. To provide a secure and sufficient support for my novel equalizing device, I employ a pair of supporting bars 11-11 which are spaced apart a sufficient distance to receive the equalizing device between them (see Fig. 3), and are securely fastened to the underside of the car frame channel members 9. The rear ends of the bars 11-11 are further supported by a pair of vertical threaded rods 12 secured at their upper ends to the car and at their lower ends engaging the orificed flanges of a cross bar 13, the rods being equipped with nuts which secure them to the cross bar.

The frame in which the moving parts of my equalizing device are assembled as a unit includes a pair of frame blocks 14-14 which as shown, may be formed of short sections of channel iron arranged to severally rest upon and bolted to the supporting bars 11-11; a cross frame bar 15 arranged above and riveted at its opposite ends to the two blocks 14; a pair of vertical bracket plates 16-16 of angle iron riveted at their top ends through their flanges to the cross-bar 15; and a bearing block 17 arranged above and secured to said cross-bar. Fixed in seats in the lower ends of the bracket plates 16 and in effect forming a part of the frame work of the devices is a short cylindrical shaft 18 which provides a pivot bearing for a group of parallel rocking equalizing levers of double or two part construction. In the present in-

stance, as illustrated, (see Figs. 3 and 4) the group consists of five double levers to provide for equalizing the strain of the five compensating cables, and two of the levers, marked 19, are longer than the remaining three, which are marked 20. Each lever consists of a pair of flat bars, *a-a*, which are connected at their front ends by a cross piece *b* providing for attachment to the compensating cables 5, and to provide proper clearance between the lever members, thin washers are interposed between them. Similar washers are arranged between each bracket plate and the adjacent bar.

The connection of the compensating cables to the equalizing levers may conveniently be made by shackle bolts 20 secured by sockets to the cables and having threaded upper ends severally extending through orifices in the cross-pieces *b* of the levers, the bolts being each equipped with nuts 21 and a washer having a rounded lower face engaging a seat on the adjacent cross piece of the lever. The threaded upper end of the shackle bolts are formed with a keyway to provide a non-rotatable connection of the bolts and the equalizing levers and counteract any tendency of the compensating cables to twist in either direction.

Between the plates *a-a* of each double equalizing lever is pivoted a lower pulley 22, the distance of the axes of the two pulleys 22 mounted in the longer levers 19 from the axis of the bearing shaft 18 being in the same proportion to the effective length of levers 19 as the distance of the axes of the three pulleys, marked 23, mounted in the shorter levers 20 is to the effective length of said levers 20, i. e., the stress ratios of all the levers with respect to the points of attachment of the cables and the pivots of the lower pulleys are the same. It evidently results from this construction that equal stresses upon the car, sustained through the lower pulleys, whether the pulleys 22 carried by the longer levers 19 or the pulleys 23 carried by the shorter levers 20 will balance equal opposite stresses acting on the compensating cables through the ends of the levers connected to them. It is further obvious that the shackle bars, and also the pulleys, will be disposed in zig-zag or staggered relation to each other.

The bearing block 17 before mentioned may conveniently be formed of a metal casting cored and machined to provide suitable stationary pivot bearings for four parallel upper pulleys, marked 24, which are arranged obliquely with respect to the lower pulleys. The stationary mounted upper pulleys and the oscillatably mounted lower pulleys are connected by an equalizing cable 25 which is equipped with rope sockets 26 providing anchorage for the ends of the cable to the cross frame bar 15 of the device. From

its anchorage at one end the equalizing cable engages the lower and upper pulleys in alternation, the obliquity of the upper pulleys being such as to permit the opposite vertical reaches of the loop of the cable engaging it to track readily in the inclined direction shown to the grooves of the two adjacent lower pulleys which lie below it.

Since the compensating cables are of the same size, the portions below the car will in all positions be of the same weight and the stress of gravity of such portions upon the equalizing levers will be the same, while the cables are individually free to assume a higher or lower position as induced by differential travel of the cables upon the equalizing drum arising from the causes before explained, the tension upon the cables being equalized through the equalizing cable and pulleys.

To limit the extent of downward movement of the equalizer levers which might occur in case of breakage of the equalizing cable, and in such event provide a support for the ends of the compensating cables at a position a short distance below their normal working position, I provide a safety plate 27 which extends transversely underneath said levers and by a pair of bolts 28 equipped with nuts is securely fastened to the cross frame bar 15 of the device.

It will be noted that while perfect equalization or distribution of stress among the different compensating cables is attained and at the same time a vertical variation in the position of the ends of the equalizing levers and consequently difference in travel of the compensating cables is permitted, yet the vertical movement of the lower pulleys is small as compared with that of the cable ends, i. e., the movement of the latter is multiplied by the levers; so that a greater variation in travel of the cables is permitted than in the case of equalizers of the cable type heretofore known.

I claim:

1. In a device for equalizing the strain upon the members of a group of cables connected to a stress-receiving body and subject to joint stress, a plurality of levers severally pivotally connected to said body and having corresponding free ends severally connected to said cables, a plurality of pulleys severally pivoted to said levers, a plurality of other pulleys mounted on said body, and an equalizing cable anchored at its ends to said body and engaging said first-mentioned pulleys and second-mentioned pulleys in alternation.

2. In a device for equalizing the strain upon the members of a group of cables connected to a stress-receiving body and subject to joint stress, a plurality of levers severally pivotally connected at one end to said body and severally connected at the other end to said cables, a plurality of pulleys severally

intermediately pivoted to said levers, a plurality of other pulleys mounted on said body, and an equalizing cable anchored at its ends to said body and engaging said first-mentioned pulleys and second-mentioned pulleys in alternation.

3. In a device for equalizing the strain upon the members of a group of cables connected to a stress-receiving body and subject to joint stress, a plurality of parallel horizontally disposed levers severally pivotally connected at one end to said body and severally connected at the other end to said cables, a plurality of lower pulleys intermediately pivoted to said levers, a plurality of upper pulleys mounted on said body above said lower pulleys, and an equalizing cable anchored at its ends to said body and engaging said lower pulleys and upper pulleys in alternation.

4. In a device for equalizing the strain upon the members of a group of cables connected to a stress-receiving body and subject to joint stress, a plurality of levers severally pivotally connected at one end to said body and severally connected at the other end to said cables, said levers being partly of one length and partly of another and being connected to the cables in staggered relation, a plurality of pulleys severally intermediately pivoted to said levers at distances from the axes of the levers proportionate to their length, a plurality of other pulleys mounted on said body, and an equalizing cable anchored at its ends to said body and engaging said first-mentioned pulleys and second-mentioned pulleys in alternation.

5. An equalizing structure according to claim 2 in which the levers therein mentioned consist of a pair of parallel plates and the therein first mentioned pulleys are severally mounted between the plates of the associated pair.

6. In a device for equalizing the strain upon the members of a group of cables connected to a stress-receiving body and subject to joint stress, a plurality of levers severally pivotally connected to said body, the ends of said cables being equipped with shackle bolts and said bolts being connected to the ends of the levers by an adjustable splined connection, a plurality of pulleys severally pivoted to said levers, a plurality of other pulleys mounted on said body, and an equalizing cable anchored at its ends to said body and engaging said first-mentioned pulleys and second-mentioned pulleys in alternation.

7. An equalizing structure according to claim 2 in which the downward movement of the ends of the levers is limited by a safety plate connected to the stress-receiving body.

8. In a device for equalizing the strain upon the members of a group of cables connected to a stress-receiving body and subject to joint stress, a plurality of levers severally

5 pivotally connected to said body, a plurality of pulleys severally pivoted to said levers, said levers being severally connected to said cables at corresponding points of attachment with reference to their fulcrums and the pivots of said pulleys, a plurality of other pulleys mounted on said body, and an equalizing cable anchored at its ends to said body and engaging said first-mentioned pulleys and second-mentioned pulleys in alternation.

10 In testimony whereof, I have subscribed my name.
